INVENTOR

UNITED STATES PATENT OFFICE.

FRANK J. CURTIS, OF BEN AVON, PENNSYLVANIA.

ROTARY PUMP.

999,753.

Specification of Letters Patent. Patented Aug. 8, 1911.

Application filed April 10, 1909. Serial No. 489,114.

To all whom it may concern:

Be it known that I, FRANK J. CURTIS, residing at Ben Avon, in the county of Allegheny and State of Pennsylvania, a citizen of the United States, have invented or discovered certain new and useful Improvements in Rotary Pumps, of which improvements the following is a specification.

In an application filed November 12, 1908, Serial No. 462,304, I have described and claimed certain improvements in rotary pumps, including a construction whereby the blades or vanes are moved outwardly to bear against the periphery of the cylinder by a pressure proportional to the height of the discharge column from the pump, when the pocket immediately in front of a given blade is subjected to discharge pressure.

The invention described herein relates to certain further additional improvements whereby each blade will be subjected to a pressure forcing it outward, so as to bear against the inner periphery of the cylinder, proportional to the height of the discharge column, such pressure becoming effective against the blade or vane after passing the inlet port.

It is a further object of the invention to provide for a balancing of pressures operative against the vanes in the direction of rotation. The invention is hereinafter more fully described and claimed.

In the accompanying drawings forming a part of this specification, Figure 1 is a sectional elevation of my improved pump; Fig. 2 is a transverse section on a plane indicated by the line II-II Fig. 1, and Fig. 3 is a side elevation with one of the side plates removed and the rotary member with its blades indicated in dotted lines.

In the practice of my invention the pump is formed by a drum 1 provided at one point with an inlet opening or nozzle 2 and at another point with a discharge nozzle 3, and having removable heads 4, closing the ends of the drum and provided with bearings 5 for the shaft of the rotary member, said bearings being eccentric to the drum. The rotary member 14 is provided with radial sockets 15 for the reception of the blades or vanes, which consist preferably of outer portions 16 formed of suitable material as vulcanized rubber or hard wood, preferably the former, as by reason of its density and non-fibrous character its surfaces can be made very smooth and will therefore be

very durable, outlasting any other materials heretofore employed. And further the vulcanized rubber blades will not change in shape or dimensions or become softened by absorption of water, as do blades made of the densest woods, which when the pumps are employed in mines, should be of a character capable of resisting the action of acid contained in such water. As stated in the application referred to the blades or vanes, when passing across the outlet port, are subjected to a pressure tending to force them inwardly, proportional to the height of the liquid column in the discharge passage. Such inward movement is prevented in the construction described and shown in the application referred to by forming ports or passages extending from points on the periphery of the rotary member in front of the blades or vanes to the inner ends of the sockets 15, so that the inner ends of the blades are subjected to outwardly acting pressure and there will be no tendency whatsoever for an inward movement of the blades as soon as a pocket is open to discharge pressure. As thus constructed the blades or vanes will be subjected to the discharge pressure only when the blade or vane forming the front wall of a pocket passes beyond the first edge of the discharge port, so that the pressure in the discharge will act on the water in such pocket and the pressure will be transmitted through the port or passage to the socket 15 in the next succeeding blade forming the rear of the water pocket.

It has been found that the centrifugal action will not always be sufficient to hold the blade or vane in contact with the inner periphery of the cylinder, after it has passed the inlet port and before the pocket in advance of any one blade is in connection with the discharge passage. In order to insure a firm bearing of the blades as they pass beyond the inlet port, a connection is formed from the discharge opening to each socket 15 in the rear of the blade or vane therein, as such blade passes the inlet port. Such connection is conveniently made by a passage 21 preferably extending along each end of the cylinder to a point where they will register with the ends of the sockets 15, which, as shown in Fig. 2, extend entirely along the rotary member, just as the blade carried by such socket passes the rear edge *a* of the inlet port. Where the end of the

cylinder proper is formed by a removable plate 22 as in the construction shown, this passage 21 is conveniently formed by slotting the plate or plates, as shown in Figs. 1, 5 2 and 3. It is preferred that the passage should be so constructed and arranged as to be in register with the ends of the sockets 15 when the blades or vanes pass beyond the edge *a* of the inlet port, to continue in 10 register with the sockets at least until after the blades or vanes have reached such a position where it has been pushed back into the socket by the wall of the cylinder.

I claim herein as my invention:

- 15 1. In a rotary pump, the combination of a cylinder having inlet and outlet ports, a rotary member eccentrically mounted in the cylinder and provided with radial sockets, vanes mounted in the sockets, means for applying fluid pressure acting to force the vanes outwardly during their passage from a point beyond the inlet port to a point beyond the outlet port, and means for relieving such pressure upon the vanes while 20 passing the inlet port.
- 20 2. In a rotary pump, the combination of a cylinder having inlet and outlet ports, a 25

rotary member eccentrically mounted in the cylinder and provided with radial sockets, vanes mounted in the sockets, means for applying discharge pressure acting to force the vanes outwardly during their passage from a point beyond the inlet port to a point beyond the outlet port, and means for relieving such pressure upon the vanes while 30 35 passing the inlet port.

3. In a rotary pump, the combination of a cylinder, a rotary member eccentrically mounted therein and blades or vanes movably mounted in the rotary member and 40 formed of a non-metallic non-porous material.

4. In a rotary pump, the combination of a cylinder, a rotary member eccentrically mounted therein, and blades or vanes 45 formed of vulcanized rubber movably mounted in the rotary member.

In testimony whereof, I have hereunto set my hand.

FRANK J. CURTIS.
